(57) **CLAIM**

I claim the ornamental design for a display board, as shown
and described.

DESCRIPTION

FIG. 1 is a front perspective view of a first embodiment of a
display board of the present invention.

FIG. 2 is a front view of the display board of FIG. 1.

FIG. 3 is a top view of the display board of FIG. 1.

FIG. 4 is a bottom view of the display board of FIG. 1.

FIG. 5 is a right-side view of the display board of FIG. 1.

FIG. 6 is a left-side view of the display board of FIG. 1.

FIG. 7 is a rear view of the display board of FIG. 1.

FIG. 8 is a front perspective view of a second embodiment of
a display board of the present invention.

FIG. 9 is a front view of the display board of FIG. 8.

FIG. 10 is a top view of the display board of FIG. 8.

FIG. 11 is a bottom view of the display board of FIG. 8.

FIG. 12 is a right-side view of the display board of FIG. 8.

FIG. 13 is a left-side view of the display board of FIG. 8; and,
FIG. 14 is a rear view of the display board of FIG. 8.

The broken lines near the top of the display boards of FIGS.
1, 2, 8, and 9, and the broken lines on the rear of the display
boards of FIGS. **7 and 14**, are included for the purpose of
illustrating environment and form no part of the claimed
design.
